(57) CLAIM

The ornamental design for a bowfishing reel, as shown and described.

DESCRIPTION

FIG. 1 is perspective view of the bowfishing reel in accordance with the invention;

FIG. 2 is a front view thereof;

FIG. 3 is a rear view thereof;

FIG. 4 is a side view thereof;

FIG. 5 is an opposite side view of FIG. 4;

FIG. 6 is a top view of the invention; and,

FIG. 7 is a bottom view of the invention.

The broken lines shown in FIGS. 1-7 depict environmental structure and are for illustrative purposes only and form no part of the claimed design.
